UNITED STATES PATENT OFFICE

ORVAL R. PLATTER, OF NORTH VERNON, INDIANA

SOUND AMPLIFIER

Application filed October 3, 1927. Serial No. 223,721.

My invention relates to horns or sound amplifiers designed to be used with radio sets, phonographs and the like and it is an object of the invention to provide a device of this character which will amplify the tone waves of the voice and musical instruments and will emit such tone waves in a manner so that they may be clearly and distinctly heard and with the suppression of discordant sounds.

10 It is a further object of the invention to provide a horn which is of simple, inexpensive and compact construction and one which is attractive in appearance, all as will be hereinafter more particularly described and 15 claimed.

Referring to the accompanying drawings which are made a part hereof and on which similar reference characters indicate similar parts,

20 Figure 1 is a horizontal section of a self-containing power speaker cabinet of a radio set, and,

Figure 2, a section on the line 2—2 of Fig. 1.

25 In the drawings reference character 10 indicates a cabinet provided at its front with a grille 11 having a silk gauze background 12, and rubber-tipped feet 13, said cabinet being preferably finished in a manner similar to 30 other furniture to render the same attractive in appearance so that it will grace the surroundings in which it is placed.

Within the cabinet 10 is a vertically disposed transverse partition member 14 of a 35 height equal to the depth of the cabinet and arranged at an angle with its front edge at the front corner of the cabinet and its rear edge in contact with the rear wall of the cabinet in slightly spaced relation from the 40 central portion of the same. Another vertically arranged partition member 15 is disposed substantially two-thirds of the distance from the front to the rear wall of the cabinet in substantially parallel relation 45 thereto and joins another partition member 16 disposed in vertical relation transversely of the cabinet or in substantially parallel 50 relation to the end walls of the same. A fourth partition 17 is mounted substantially mid-way between the partition member 15

and the front wall of the cabinet in vertical relation and extends from the front end of the partition 16 laterally to the end of the cabinet in substantially parallel relation to the front and rear walls of the same. The 55 partition member 16, adjacent its lower end, is connected to the large end 18 of a speaking tube, an opening being provided in the partition for receiving such enlarged end. The speaking tube tapers from its large to its 60 small end and extends from the partition 16 perpendicularly towards the end of the cabinet and is then provided with a forwardly extending portion 19 which extends through an aperture in the partition 17 from whence 65 the horn is provided with a substantially straight, longitudinally disposed portion 20 extending across the front of the cabinet, from which projects rearwardly a side portion 21 which extends through an opening in 70 the partition 14 and has at its rear end a longitudinally extending rear portion 22 which carries a power speaker unit 23 at its end.

A horn or loud speaker of this construction 75 possesses an amplifying chamber connected with a long tone chamber which is found very desirable, said tone chamber being constructed of a plastic, resonant, fibrous material and one in which the true, undistorted 80 qualities of the tones are amplified prior to their emission from the device. The various sections of the horn which are wound around the interior of the cabinet do not interfere with the emission of sound from the sound box as the walls of the horn deflect the sound waves. The partition members 14, 17 and 16 through which the horn or speaking tube extends are provided with apertures of a 85 size to snugly accommodate the said horn and serve to support the same in a rigid manner and to form a strong cabinet structure although the members are formed of relatively thin material.

90 It will be obvious to those skilled in the art that various changes may be made in my device without departing from the spirit of the invention, and I, therefore, do not limit myself to what is shown in the drawings and 100

described in the specification, but only as set forth in the appended claims.

Having thus fully described my said invention, what I claim as new and desire to secure by Letters Patent, is:

- 5 1. A loud speaker comprising a cabinet open at one side, a plurality of upright partition members forming an amplifying chamber, and a sound receiving tube extending 10 from one side of said amplifying chamber around the cabinet through said partition members, substantially as set forth.
- 15 2. A loud speaker comprising a cabinet open at one side, a plurality of partition members forming an amplifying chamber, a tapered sound receiving and conveying tube coiled within said cabinet and having its large end terminating in one of said partitions adjacent the center of the amplifying chamber, 20 substantially, as set forth.
- 25 3. A device of the class described comprising an amplifying chamber formed of a plurality of flat surfaces assembled to form a flared mouth, one of said flat surfaces being provided with an opening adjacent the center of the amplifying chamber, a tapered tube coiled around said amplifying chamber and having its large end disposed in said opening, the larger and small ends of said tapered 30 tube being disposed in overlapping relation, substantially as set forth.
- 35 4. A device of the class described comprising an amplifying chamber formed of a plurality of flat surfaces assembled to form a flared mouth, one of said flat surfaces being provided with an opening adjacent the center of the amplifying chambers, a tapered tube coiled around said amplifying chamber and having its large end disposed in said 40 opening, the larger and small ends of said tapered tube being disposed in overlapping relation, said tube having portions disposed both in front of and behind its large end, substantially as set forth.
- 45 5. A sound amplifier comprising a substantially rectangular cabinet, a partition member disposed at an angle transversely across one end of said cabinet, a longitudinally disposed partition member joining the rear portion of 50 said first mentioned partition member, a central transverse partition member, a tapered sound tube having its large end disposed in said central partition and extending therefrom in a direction opposite the first mentioned partition then forwardly and across the front of the cabinet then rearwardly to the rear of the cabinet and across the same to the opposite end, substantially as set forth.

In witness whereof, I have hereunto set my hand at North Vernon, Indiana, this 30th day of September, A. D. nineteen hundred and twenty-seven.

ORVAL R. PLATTER.
